(57) CLAIM

The ornamental design for dance footwear, as shown and described.

DESCRIPTION

FIG. 1 is a front perspective view of a dance footwear showing my new design in use condition;

FIG. 2 is a lateral side elevation view thereof;

FIG. 3 is a medial side elevation view thereof;

FIG. 4 is a front view thereof;

FIG. 5 is a rear view thereof;

FIG. 6 is a top view thereof; and,

FIG. 7 is a bottom view thereof.

The broken line showing of the sole, leg and foot is for illustrative purposes only and forms no part of the claimed design.
